UNITED STATES PATENT OFFICE.

REBECCA E. SHANLEY, OF WASHINGTON, DISTRICT OF COLUMBIA.

DESIGN FOR A BADGE, EMBLEM, OR SIMILAR ARTICLE.

54,335.

Specification for Design.

Patented Dec. 23, 1919.

Application filed October 1, 1918. Serial No. 256,475. Term of patent 14 years.

To all whom it may concern:

Be it known that I, REBECCA E. SHANLEY, a citizen of the United States, residing at Washington, District of Columbia, have invented a new, original, and ornamental Design for a Badge, Emblem, or Similar Article, of which the following is a specification, reference being had to the accompanying drawing, forming part thereof.

The drawing is a front elevation of a badge or button showing my new design.

I claim:

The ornamental design for a badge, emblem, or similar article, as shown.

REBECCA E. SHANLEY.
